UNITED STATES PATENT OFFICE.

FREDERICK E. POLLARD, OF NEW YORK, N. Y.

DESIGN FOR A WARDROBE.

SPECIFICATION forming part of Design No. 27,671, dated September 21, 1897.

Application filed June 4, 1897. Serial No. 639,475. Term of patent 14 years.

To all whom it may concern:

Be it known that I, FREDERICK E. POLLARD, a citizen of the United States, residing at New York, in the county of New York and State of New York, have invented a new and useful Design for a Wardrobe, of which the following is a specification.

The design is shown in the accompanying drawing, forming part of this specification, which drawing illustrates a perspective view of a wardrobe embodying the design.

Referring to the drawing and in detail, the design for wardrobes comprises a cornice 10 at the top and two flexible rolling doors 11 and 12, which close to a mullion 13 at the center. The front at each side of the doors is

paneled at 14. The ends are also paneled at 15. Near the back is a false partition 16, with screenwork 17, and a number of slats 18, having hooks 19, which break joints. ²⁰

Having thus fully described and illustrated the design, what is claimed is—

The design for a wardrobe, substantially as herein shown and described.

In testimony whereof I have hereunto set ²⁵ my hand in the presence of two subscribing witnesses.

FREDERICK E. POLLARD.

Witnesses:

LOUIS W. SOUTHGATE,
PHILIP W. SOUTHGATE.
